UNITED STATES PATENT OFFICE.

ROBERT SCHAELLIBAUM, OF PROVIDENCE, RHODE ISLAND.

GRID FOR OPENERS, SCUTCHERS, AND THE LIKE MACHINES.

No. 905,237.

Specification of Letters Patent.

Patented Dec. 1, 1908.

Application filed June 4, 1906. Serial No. 320,097.

To all whom it may concern:

Be it known that I, ROBERT SCHAELLIBAUM, citizen of Switzerland, residing at Providence, Rhode Island, United States of America, have invented new and useful Improvements in and Connected with Grids for Openers, Scutchers, and the Like Machines.

This invention relates more particularly to improvements on an invention for which Letters Patent No. 447,365, March 3rd, 1891, have been granted to me and in which a comb with metal knife-edged foundation is employed in combination with a grid and beater. Hitherto the said foundation has been flat in section and its sides quite plain which made the drilling of the holes for the reception of the pins at the required acute angle to the foundation very difficult.

The object of my present invention is to provide means whereby the drilling of the said pin holes in the comb foundation is rendered much easier and possible at an acute angle to the general surface thereof than hitherto has been the case and at the same time the action of the comb is improved in connection with means for supporting and securing the said comb. I attain these objects by the means illustrated in the accompanying drawing, which represents a cross section of a comb and support constructed in accordance with my invention.

In carrying out my invention and referring to the drawing I form the top edge *a* of the comb foundation *b* as usual knife-edged, while instead of leaving each side plain, I provide same with corrugations *c*. In every alternate side of these corrugations I drill a row of holes passing through the opposite corrugation side *c* on the other side of the foundation as near at a right angle to the said sides as possible, which holes serve for the reception of the comb pins *d* securely driven into the same. To facilitate the fix-

ing of the said pins at a very acute angle to the general surface of the comb, I may form 45 the said corrugations slightly displaced in relation to each other as shown. By preference I form the said corrugations angular in section and the sides through which the pin *d* passes narrower than the others to prevent 50 the lodging of any fibers in the corrugations.

The corrugations in the top of the foundation render the action of the comb pins also more effective as they retain the fibers under treatment to a certain extent, that is to say, 55 they are caused to pass slower through the pins *d* which gives the draft created by the beater more time to free them from impurities.

The comb described is secured, say by 60 screws *f* to an angle iron *e*, which on the top is corrugated to correspond with and engage in the corrugations at the back of the comb foundations *b* and thereby render the comb very secure on the angle iron *e* besides preventing the pins *d* which might come loose 65 from dropping or falling out.

I claim:

In an opener, scutcher and the like machine, in combination with a beater and a 70 grid, a flat stationary comb comprising a metal foundation, having corrugations in both sides, pins through every two alternate opposite sides of the said corrugations at a 75 right angle thereto and a support having a flat corrugated surface in which the corrugations at the back of the said comb foundations engage, all substantially as and for the purpose set forth.

In testimony whereof I have signed my 80 name to this specification in the presence of two subscribing witnesses.

ROBERT SCHAELLIBAUM.
